(57) **CLAIM**

I claim the ornamental design for a knitting indicator ring for counting loops, as shown and described.

DESCRIPTION

FIG. 1 is a perspective view of a knitting indicator ring for counting loops showing my new design;
FIG. 2 is a front view of the same ring;
FIG. 3 is a rear view of the same ring;
FIG. 4 is a top plan view of the same ring;
FIG. 5 is a bottom view of the same ring;
FIG. 6 is a right side view of the same ring; and,
FIG. 7 is a left side view of the same ring.
